UNITED STATES PATENT OFFICE

141,692

DESIGN FOR A LENS MOUNT OR THE LIKE

Otto R. Nemeth, Chicago, Ill., assignor to Products Development, Inc., Chicago, Ill., a corporation of Illinois

Application January 29, 1945, Serial No. 117,665

Term of patent 14 years

(Cl. D61—1)

To all whom it may concern:

Be it known that I, Otto R. Nemeth, a national of Czechoslovakia, residing at Chicago, in the county of Cook and state of Illinois, have invented a new, original, and ornamental Design for a Lens Mount or the like, of which the following is a specification, reference being had to the accompanying drawing, forming part thereof.

Figure 1 is a perspective view of a lens mount or the like embodying my new design, the essential features thereof being shown in full lines.

Fig. 2 is a top plan view of the mount on a reduced scale, and showing how it appears disassociated from the lens holding tube which in Fig. 1 is shown in broken outline.

Fig. 3 is an end view of the mount on the same reduced scale and in the same condition as Fig. 2.

I claim:

The ornamental design for a lens mount or the like, substantially as shown and described.

OTTO R. NEMETH.
